FIG. 1.

FIG. 4.

FIG. 2.

FIG. 3.

To all whom it may concern:

Be it known that I, Donald E. Dailey, a citizen of the United States of America, residing at Old Petersburg Road, Center Township, in the county of Vanderburgh and State of Indiana, have invented a new, original, and ornamental Design for a Room Cooler, of which the following is a specification, reference being had to the accompanying drawings, forming part thereof.

In the drawing:

Fig. 1 is a perspective view of a room cooler embodying my design and showing the front, top and one side thereof;

Fig. 2 is a side elevational view of the room cooler and showing the side opposite from that shown in Fig. 1;

Fig. 3 is a top plan view of the room cooler; and Fig. 4 is a section taken on line 4—4 of Fig. 1 to show the actual contour of the front panel.

The dominant feature of my design resides in the portions illustrated by full lines in the drawing.

I claim:

The ornamental design for a room cooler, as shown and described.
